UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

SHEET-THROW-OUT MECHANISM.

Application filed November 5, 1917, Serial No. 200,314. Renewed January 8, 1923.

To all whom it may concern:

Be it known that I, HENRY A. WISE Wood, a citizen of the United States, residing at New York, in the county of New York and 5 State of New York, have invented a new and useful Sheet-Throw-Out Mechanism, of which the following is a specification.

This invention relates to a throw-out device for printing presses for the purpose of 10 throwing out a sheet when desired for inspection or other purposes.

The principal objects of the invention are to provide a simple construction for this purpose which will always work in such a 15 way as to avoid disturbing the pile of papers delivered, and to provide an arrangement which will work at any speed for this purpose.

Further objects and advantages of the invention will appear hereinafter.

Reference is to be had to the accompanying drawings, in which—

Fig. 1 is a plan of a preferred form of the invention applied to a usual type of folder, 25 and

Fig. 2 is a side elevation of the same.

As is well known, it is necessary occasionally to take out a folded sheet for inspection, but in modern high speed presses this 30 always seriously disturbs the pile of papers as delivered.

As has been indicated above, the principal object of this invention is to avoid this difficulty and at the same time to provide for 35 throwing out a single folded product at a time, in such a way that the uniform delivery of the rest of the product will be continued automatically.

The invention is shown as used in connection with a usual folding cylinder 1 and folding rolls 2 of a printing machine, delivering in the ordinary course to fan buckets 3 on a shaft 5. This shaft 5 drives a delivery shaft 4 through a train of gears 6, 40 7, 8 and 9. For the purpose of this invention a disc 10 having depressions 11 in its periphery is located on the shaft 4 so as to rotate with it. In the form illustrated there are five of these depressions 11 which, in view of 45 the ratio of the gearing illustrated, will act to throw out one paper in ten by the mechanism herein shown. It will be clear, however, that by changing the number of depressions 11 the papers can be thrown out

with greater or less frequency, but always 55 at regular intervals if kept in operation long enough.

Adjacent to the periphery of the disk 10 is a shaft 12 on which is mounted a roller lever 13 having a roller 14 at its end which engages with the periphery of the disc 10, and if allowed to is capable of entering the depressions 11 as the disc rotates. If it enters these depressions obviously it will oscillate the shaft 12. For the purpose of transmitting this motion there is a switch lever 15 fixed on the shaft 12, and there is a spring lever 16 also on this shaft for controlling the shaft itself. The switch lever 15 is connected to operate a series of switches 18 60 mounted on arms 37 which are fixed to a cross shaft 19. This shaft is also provided with an arm 20 which is adjustably connected with a rod 21 pivoted to the end of the switch lever 15. The switches 18 are arranged to swing from the position shown in full lines in Fig. 2 to the position shown in dotted lines in that figure where they come into the path of the paper issuing from the folding rolls 2 and divert it from the fan buckets as will appear later.

For the purpose of holding the roller 14 against the periphery of the disc 10 the spring lever 16 is connected with a rod 22 having a spring 23 thereon operating between a collar 24 fixed on the rod and a stationary poppet 25. This spring therefore forces the end of the lever 16 down and turns the shaft 12 so as to force the roller 14 yieldingly against the periphery of the disc 10.

The means by which the operation of the device is controlled manually comprises a trip handle 26 adjustably connected with a rod 27. This rod is provided with a spring 28 upon it which operates between a collar 29 fixed on the rod and a fixed poppet 31 engaging against a stop 30 adjustably connected with the rod 27. In the position shown in full lines in Fig. 2 the handle is moved down by the action of the spring in forcing the rod 27 to the right and therefore swinging the arm 17, to which the rod is connected, to the right. This arm 17 is mounted on a shaft or stud 32 which is provided with a trip toe 33. This trip toe, in the position shown in Fig. 2 in full lines, rests under the end of a third arm 36 fixed on the shaft 12

and holds the shaft and its several arms in the position shown in full lines. When, however, the handle 26 is raised against the stop pin 38 the arm 17 is pulled over so as to release the toe 33 from under the arm 36 and allow the spring 23 full freedom to turn the shaft 12 in one direction so as to allow the roller 14 to enter the depressions 11 in the disc 10.

10 It will be understood that the trip toe 33 is adapted to move just to such position and is just long enough to hold the roller 14 practically in contact with the circular surface of the disc 10 and prevent it entering the depressions. Therefore, when the trip handle is in the position shown in Fig. 2 this throw-out mechanism is out of operation.

15 It will be observed that there is a series 20 of stationary guides 34 or stops supported by a bar 35 on the frame and projecting into a position to receive a sheet or folded product from the switches 18.

20 In operation, when it is desired to throw 25 out a folded product for inspection the handle 26 is lifted against the stop pin 38, thus moving the trip toe 33 from under the lock lever 36 into the dotted line position in Fig. 2. The circular part of the disc 10 receives 30 the pressure from the roller 14 due to the spring 23 and holds the roller in substantially the position in which it is when the throw-out mechanism is at rest, but when 35 a depression 11 comes into registration with the roller 14 the roller will now be free to enter it and this will cause the shaft 12 to swing slightly, taking the arm 15 with it of course, and moving the rod 21, arm 20 and shaft 19 so as to drop the switches 18 into 40 the dotted line position shown in Fig. 2. This, it will be understood, is timed by the shaft 4, which is positively geared to the shaft 5, and therefore the parts can be designed 45 so that it will take place just in time to receive the advancing end of a folded product on the switches 18. In this way one sheet or product is diverted directly from the rolls 2 away from the usual path and guided over the switches 18 into the stationary guides 34. If the trip handle 26 is held 50 up against the stop 38 every tenth paper will be delivered in this way, the switches 18 immediately moving out of operative position after one paper has been passed over them.

55 Ordinarily, however, only one sheet being required for inspection, the handle 26 is held up only until the one sheet required has been delivered and then released as there is plenty of time in which the spring can turn it down before this throw-out device will operate again.

60 The rise of the roller 14 out of one of the depressions 11 on to the circular part of the disc drives the arm 36 up so that the toe 33 can be moved under it at any time

before the roller moves into another depression.

Although I have shown only a single form of the invention and illustrated it as applied to a particular form of folding apparatus, I am aware of the fact that modifications can be made therein by any person skilled in the art and that it can be applied to other types of folders without departing from the scope of the invention as expressed in the claims.

75 Therefore I do not wish to be limited in these respects, but what I claim is:

1. In a device of the character described, the combination with a folding and a delivery mechanism, of a switch connected therewith for diverting a single folded product coming from the folding mechanism, and preventing its going to the delivery mechanism, mechanically operated means for projecting said switch into operative position, means for normally preventing the operation of the mechanically operated means, a hand lever, and means connected with the hand lever for withdrawing the operating preventing means and allowing the mechanically operated means to act.

2. In a printing machine, the combination with a folding and a delivery mechanism, of independently controlled and constantly acting means connected therewith for diverting a folded product coming from the folding mechanism and directing it out of its normal course, and then automatically continuing the next folded product in its usual path into the delivery mechanism.

3. The combination with a folding and delivery mechanism, of manually controlled means operated by the delivery mechanism in synchronism therewith for periodically diverting a folded product one at a time from a series coming from the folding mechanism and preventing its going to the delivery mechanism.

4. The combination with a folding device, of a switching device located normally out of the path of said folded products, and yielding means for projecting said switching device into the path of the folded products in time to receive one as it leaves the folding device and then automatically retracting it.

5. The combination with a folding device adapted to deliver its product in a certain path, of switches arranged adjacent thereto normally out of the path of said folded products, a shaft, and means operated by said shaft for projecting said switches into the path of the folded products in time to receive a single one and then automatically withdrawing them therefrom.

6. The combination with a folding device, of switches arranged adjacent thereto, a shaft, means operated by said shaft for projecting said switches into the path of the folded products in time to receive one directly from the folding device and then automatically

withdrawing them therefrom, and means for receiving the folded product from said switches.

7. The combination with a folding device 5 adapted to deliver its products in a certain path, of switches arranged adjacent thereto, a shaft, means operated by said shaft for projecting said switches into the path of the folded products in time to receive a single one, means for normally preventing the operation of the first-named means, a lever, and means connected with the lever for withdrawing the operating preventing means and allowing the first-named 15 means to act.

8. The combination with a folding device adapted to deliver its products in a certain path, of switches arranged adjacent thereto, a rotary disc having a general circular surface 20 face with a notch therein, a spring-pressed member connected to always tend to operate said switches into position to throw out a sheet, the circular part of said disc constituting means for preventing the spring-pressed member from acting and the notch permitting the spring-pressed member to act when the notch reaches an operative point, whereby the switches will be projected into the path of the products at a 25 definite point in the operation of the machine.

9. In a throw-out device, the combination of a rotary disc having a circular surface provided with a notch therein, a shaft having an arm thereon provided with a roller engaging said surface and adapted to enter said notch, spring-pressed means for forcing the roller against said surface and into the notch, an arm on the shaft, a toe adapted 40 to move under said arm and hold it in such position as to prevent the spring-pressed means from moving the roller into the notch, manually operated means for withdrawing said toe, a folding device, and a set 45 of switches connected with the shaft to be operated when the roller enters the notch.

10. In a throw-out device, the combination of a rotary disc having a circular surface provided with a plurality of notches therein, a roller engaging said surface and adapted to enter said notches, spring-pressed means for forcing the roller against said surface and into the notches, a toe adapted 50 to move into position to prevent the spring-pressed means from moving the roller into the notch, manually operated means for withdrawing said toe, a folding device, and a set of switches connected with the shaft to be operated when the roller enters the notch.

11. In a throw-out device, the combination of a rotary disc having a circular sur-

face provided with a plurality of notches therein, a roller engaging said surface and adapted to enter said notches, spring-pressed means for forcing the roller against said surface and into the notches, a toe adapted to move into position to prevent the spring-pressed means from moving the roller into the notch, yielding means for normally forcing said toe into said position, independent means for withdrawing said toe, a folding device, and a set of switches connected with the shaft to be operated when the roller enters the notch. 75

12. In a throw-out device, the combination of a rotary disc having a circular surface provided with a notch therein, a movable member normally engaging said surface and adapted to enter said notch when in registration therewith, means for forcing the movable member against the surface of the disc, a toe adapted to move into position to prevent said means from moving the member into the notch, manually operated means for withdrawing the toe, and a switch arranged to be operated by said member when it enters the notch to throw out a sheet. 80

13. The combination with means for feeding sheets in a path, of switches arranged adjacent to the path normally out of position to engage the products, mechanically operated means for projecting said switches 95 into the path of the products in time to receive a single one of them and then automatically withdrawing it therefrom, and a manually operated control lever arranged and adapted to be set at any time to cause the mechanically operated means to operate the switches at a predetermined later time. 100

14. The combination with means for feeding sheets in a path, of normally inoperative means arranged to deflect a sheet from said path, of mechanically operated means for causing the sheet-deflecting means automatically to deflect a sheet from the said path, and manually operated mechanism arranged and adapted to be set at any time to cause the mechanically operated means to operate the sheet-deflecting means at a predetermined later time. 110

15. In a printing machine the combination with a folding and delivering mechanism, of means placed between the two for selecting a product from the normal stream of folded products passing from the folding to the delivering mechanisms, and for directing it out of the machine for purposes 115 of inspection.

In testimony whereof I have hereunto affixed my signature.

HENRY A. WISE WOOD
